ART OF CRACKING HYDROCARBONS

Filed June 11, 1927

UNITED STATES PATENT OFFICE.

EUGENE C. HERTHEL, OF CHICAGO, ILLINOIS, AND HARRY L. PELZER, OF HIGHLAND, INDIANA, ASSIGNORS TO SINCLAIR REFINING COMPANY, OF NEW YORK, N. Y., A CORPORATION OF MAINE.

ART OF CRACKING HYDROCARBONS.

Application filed June 11, 1927. Serial No. 198,252.

This invention relates to improvements in the cracking of heavier and higher boiling hydrocarbon oils, such as gas oil, for the production of lighter and lower boiling hydrocarbon oils, such as gasoline and gasoline-containing pressure distillates, therefrom.

In carrying out the present invention, a body of oil is maintained at a cracking temperature and vapors including vapors of the cracked product are taken off from the body under pressure. Heat for maintaining the cracking temperature and for supplying the heat required in the cracking operation is supplied to this body in two ways, both externally and internally. Oil is circulated and recirculated from the body through heating tubes and back to the body and the circulating oil is heated in the heating tubes by heating gases passed thereover. Likewise, a gaseous heating medium heated to a cracking temperature is introduced directly into the body of oil. The heat exchange with the gaseous heating medium so introduced is direct and involves no heat transfer through the walls of tubes or the like. The burden of heat transfer through the heating tubes is thus relieved by the heat so supplied to the body of oil. Further to protect the heating tubes, a bed of finely divided filtering or absorbent material is also maintained in the body of oil in the path of the oil circulating and recirculating through the heating tubes.

In addition to the desired lighter and lower boiling hydrocarbon oils, the products of the cracking reaction include pitch-like or asphaltic constituents which tend to separate upon externally heated surfaces with resulting formation of carbonaceous deposits on such heating surfaces which impede heat transfer from the heating surface to the oil and consequently tend to cause local and extreme overheating. The formation of such carbonaceous deposits, in part at least, is dependent upon the rate of heat transfer, the tendency to formation of such deposits being less at lower rates of heat transfer, and such deposits moreover are less objectionable where they occur on surfaces through which the rate of heat transfer is relatively low.

In the cracking operation of the present in-

vention, the oil is heated, in part, by circulation through externally heated heating tubes, but the burden of heat transfer through these tubes is reduced by the direct introduction of a gaseous heating medium. The tendency 55 toward formation of carbonaceous deposits in the heating tubes is thus reduced, and the objectionable effects of any such deposits that may occur are also minimized. At the same time, these heating tubes are further protected by reducing the concentration of such pitch-like or asphaltic constituents in the oil circulating through the heating tubes by circulating this oil also through a bed of filtering or absorbent material. The concentration of 60 such pitch-like and asphaltic constituents in the circulating charge of oil in the pressure still may be further controlled and regulated, as described in Letters Patent No. 1,598,136 issued August 31, 1926, by the discharge of 65 pitch-laden oil or tar and the supply of raw oil and the conjoint regulation of the discharge of pitch-laden oil or tar and the supply of raw oil to maintain the concentration of such constituents in the still charge below saturation, 70 or below an objectionable value.

The gaseous heating medium may with advantage consist of a hydrocarbon gas mixture, such as the gas mixture remaining uncondensed after separation of the condensed distillate product or after scrubbing or other suitable treatment for recovery of condensable constituents of the uncondensed gas mixture as initially separated from the distillate product. One advantageous absorbent and 80 filtering material is fuller's earth. Other absorbent earths and clays may be used in a similar way. Finely divided carbonaceous materials such as pulverized coke, however, are particularly advantageous. The gaseous 85 heating medium, particularly where it consists of a hydrocarbon gas mixture, is advantageously introduced into the body of oil in the pressure still beneath the bed of finely divided filtering or absorbent material so that 90 it is caused to pass upwardly through the bed of finely divided material as it passes upwardly through the body of oil.

The gaseous heating medium so introduced may thus act to maintain in suspension, or 100

partly in suspension, in the body of oil the finely divided material, thus assisting in promoting intimate contact between the finely divided material and the still charge and in 5 maintaining free circulation of the still charge. If a hydrocarbon gas mixture containing reactive constituents is used as a gaseous heating medium, the introduction of the gaseous heating medium at a cracking 10 temperature may also promote further reaction and combination of such constituents with constituents of the still charge. By introducing the gaseous heating medium beneath the bed of finely divided material, any 15 surface or catalytic action of such finely divided material effective to promote such reaction or combination is utilized. Where the gas mixture remaining uncondensed from the cracking operation is returned as the gaseous 20 heating medium, for example, it may contain substantial proportions of reactive constituents, particularly unsaturated constituents, which so reintroduced into the still charge may assist in improving yield or quality of 25 product.

The invention will be further described in connection with the accompanying drawings which illustrate, in a diagrammatic and conventional manner, in elevation and partly in 30 section and with parts broken away, one form of apparatus adapted for carrying out the process of the invention, but it will be understood that the process of the invention can be carried out in other and different apparatus and that the apparatus specifically illustrated is intended for the purpose of illustration only.

Referring to the drawings, the pressure still illustrated comprises a bulk supply drum 40 1, a battery of heating tubes 2, arranged in the heating flue of a furnace, and circulating connections 3, 4 and 5 including a circulating pump 6 for circulating oil from the bulk supply drum upwardly through the heating 45 tubes and back to the bulk supply drum. Arranged in the bulk supply drum 1, beneath the normal liquid level therein and entirely across the path of the circulating still charge between the circulating connections 3 to the 50 heating tubes and the circulating connections 5 from the heating tubes is a bed 7 of finely divided absorbent or filtering material. This bed of finely divided material is supported upon a suitable supporting means 8 adapted 55 to retain the finely divided material but to permit free passage of oil. This supporting means may consist, for example, of one or more screens of appropriate mesh arranged between perforated plates, or arranged between gratings as described in application 60 Serial No. 184,296 filed April 16, 1927. This latter construction is particularly advantageous for use in practicing the present invention. Arranged in the bulk supply drum be-

neath the supporting means 8 is a perforated 65 pipe or pipes 9. Connection 10 communicates with this perforated pipe. Heating coil 11, arranged in another heating furnace, is connected to the perforated pipe 9 and a compressor or other forcing means is provided 70 for forcing a gaseous heating medium through this heating coil into the still charge through perforated pipe 9.

Vapors from the bulk supply drum 1 escape through connection 12 to the lower end of the 75 reflux tower and vapors remaining uncondensed escape from the upper end of the reflux tower through connection 14 to the condenser 15 arranged to discharge into the receiver 16. The distillate product is discharged from this receiver through connection 17 and uncondensed vapors and gases through connection 18. Pressure in the system is maintained and regulated by means of valve 19, or by suitable valves arranged beyond the condenser or receiver. Connection 20 is provided for introducing raw oil into the upper end of the reflux tower 13. Reflux condensate, together with any admixed unvaporized raw oil, is returned to the circulating 80 still charge from the lower end of the reflux tower through connection 21. Connection 22 is provided for discharging tar or pitch-laden oil during operation. Connection 23 is provided for supplying cool oil to 90 the bearings of the circulating pump 6. Raw oil in excess of that required to cool and lubricate the pump bearings may be forced into the circulating still charge through the pump bearings through this connection. Connection 24 is provided for pumping out the still 95 at the end of a run and for initially charging the still at the beginning of a run.

In operation, fuel is burned in the firebox 25 of the furnace 26 and the hot products of combustion are passed over the heating tubes 2 through the heating flue in which these heating tubes are arranged. Part of the heating gases may be recirculated through this heating flue in admixture with fresh hot 100 products of combustion from the firebox by means of return flue 27 provided with suitable forcing means, such as the steam jet blower illustrated. Fuel is also burned in the furnace 28 for heating the gaseous heating medium forced through the heating coil 11. 105

In a pressure still of the type illustrated, in which the normal operating charge is about 10,000 gallons, the bed of finely divided material may consist, for example, of from 4 to 120 7 tons of 15-30 mesh fuller's earth or similar absorbent earth or clay, or of from 3 to 5 tons of 15-30 mesh pulverized coke. Agitation due to the introduction of the gaseous heating medium may effect the discharge of a part of the finely divided material in suspension in the discharged pitch-laden oil or 125

tar, during operation, and to make up for any such discharge of the finely divided absorbent or filtering material additions of such material may be made in suspension in 5 raw oil supplied to the operation.

In operation to produce gasoline or a gasoline-containing pressure distillate from gas oil character charging stock, for example, the still may be operated under a pressure in the 10 neighborhood of 125 pounds per square inch. It will be understood that higher or lower pressures may be used. Higher pressures, for example, up to 300 pounds per square inch or more, are useful where the charging stock contains 15 substantial proportions of kerosene character components. The still is initially charged and brought to operating conditions of temperature and pressure in the usual way. As the discharge of cracked vapors through 20 the reflux tower to the condenser is begun, the introduction of raw oil through the reflux tower is started and the rate at which raw oil is so supplied is regulated to condense and reflux those components of the vapors heavier 25 than desired as components of the distillate product. As soon as the discharge of vapors from the still to the condenser is begun, or shortly thereafter, the introduction of a gaseous heating medium into the charge of oil 30 in the pressure still is started. Operating to produce gasoline from a gas oil character stock under a pressure in the neighborhood of 125 pounds per square inch, for example, this gaseous heating medium may be supplied 35 at a temperature in the neighborhood of 800-850° F. or at a somewhat higher temperature. This gaseous heating medium advantageously consists of a hydrocarbon gas mixture such as that discharged from the operation after separation of the condensed distillate product. Other hydrocarbon gas mixtures, such as those resulting from coking operations carried out at atmospheric pressure 40 may also be used, alone or in admixture with such returned pressure still gas mixtures. Any of these gas mixtures may be subjected to scrubbing or other suitable treatment for the recovery of condensable constituents before being supplied to the 45 operation.

In carrying out the present invention, in the apparatus illustrated for example, it will be apparent that the heat for maintaining the body of oil in the pressure still at a cracking 55 temperature and for effecting the cracking operation is supplied by externally heating oil circulated from the body through heating tubes and back to the body and also by the direct introduction into the body of a 60 gaseous heating medium. The heat supplied directly by the gaseous heating medium assists in relieving the burden of heat transfer through the heating tubes, thus protecting the heating tubes against overheating. These

heating tubes are further protected against 65 overheating by the action of the bed of finely divided filtering or absorbent material through which the charge of oil in the pressure still is circulated in eliminating or reducing any tendency toward the formation 70 of carbonaceous deposits in the heating tubes. The formation of carbonaceous deposits in the heating tubes may be further inhibited by the regulated supply of raw oil and discharge of pitch-laden oil or tar, and the heating tubes further protected by recycling over the heating tubes in admixture with fresh hot products of combustion a part of the heating gases which have passed thereover. The invention makes possible reduction in the 80 strains to which the pressure still apparatus is subjected, particularly those due to very high heat transfer rates, without interfering with the capacity of the still.

We claim:

1. An improved method of cracking hydrocarbon oils, which comprises maintaining a body of oil at a cracking temperature and taking off vapors including vapors of the cracked product therefrom under pressure, 90 circulating oil from the body through heating tubes externally exposed to heating gases and back to the body, maintaining a bed of finely divided filtering material in the body of oil in the path of the circulating oil, and introducing a gaseous heating medium heated to a cracking temperature into the body of oil beneath the bed of finely divided filtering material.

2. An improved method of cracking hydrocarbon oils, which comprises maintaining a body of oil at a cracking temperature and taking off vapors including vapors of the cracked product therefrom under pressure, 100 circulating oil from the body through heating tubes externally exposed to heating gases and back to the body, maintaining a bed of finely divided absorbent material in the body of oil in the path of the circulating oil, and introducing a gaseous heating medium heated to a cracking temperature into the body of oil 105 beneath the bed of finely divided absorbent material.

3. An improved method of cracking hydrocarbon oils, which comprises maintaining a 115 body of oil at a cracking temperature and taking off vapors including vapors of the cracked product therefrom under pressure, circulating oil from the body through heating tubes externally exposed to heating gases 120 and back to the body, maintaining a bed of finely divided carbonaceous material in the body of oil in the path of the circulating oil, and introducing a gaseous heating medium heated to a cracking temperature into the body of oil beneath the bed of finely divided carbonaceous material.

4. An improved method of cracking hydro-

carbon oils, which comprises maintaining a body of oil at a cracking temperature and taking off vapors including vapors of the cracked product therefrom under pressure, circulat-
5 ing oil from the body through heating tubes externally exposed to heating gases and back to the body, maintaining a bed of finely divided carbonaceous material in the body of

oil in the path of the circulating oil, and introducing hydrocarbon gases heated to a 10 cracking temperature into the body of oil beneath the bed of finely divided carbonaceous material.
